CLAIM

I claim the ornamental design for a combined towel and integrated brush, as shown and described.

DESCRIPTION

FIG. 1 is a right-front perspective view of a combined towel and integrated brush, showing my new design;

FIG. 2 is an alternate right and front side perspective view thereof, shown in a flexible state;

FIG. 3 is a top plan view thereof;

FIG. 4 is a left side elevation view thereof;

FIG. 5 is a right side elevation view thereof;

FIG. 6 is a rear elevation view thereof;

FIG. 7 is a front elevation view thereof;

FIG. 8 is an alternate top plan view thereof, shown in a flat, tri-folded state; and,

FIG. 9 is a left and front perspective view thereof, shown in a peaked tri-folded state.

The dash-dash-dash broken lines seen within the claim area around the perimeter of the towel are shown to represent stitching. The combined towel and integrated brush is shown with symbolic breaks in its length in all of the figures. It is understood that patentability is based only on those portions of the article that are shown in solid lines, and the appearance of any portion of the article between the break lines forms no part of the claimed design.
